UNITED STATES PATENT OFFICE

138,086

DESIGN FOR AN ELECTRIC PLUG TAP

Louis Ludwig, New York, N. Y.

Application March 14, 1944, Serial No. 112,899

Term of patent 14 years

(Cl. D26—1)

To all whom it may concern:

Be it known that I, Louis Ludwig, a citizen of the United States of America, residing in the Borough of Queens, city of New York, county of Queens, and State of New York, have invented a new, original, and ornamental Design for an Electric Plug Tap, of which the following is a specification, reference being had to the accompanying drawing, forming a part thereof.

Figure 1 is a view in perspective, as seen gen-

erally from the front, of an electric plug tap showing my new design.

Figure 2 is a view in perspective, as seen generally from the rear, of an electric plug tap shown in Figure 1.

I claim.

The ornamental design for an electric plug tap, as shown.

LOUIS LUDWIG.
